(57) **CLAIM**

The ornamental design for a sole construction for footwear, as shown.

DESCRIPTION

FIG. 1 is a front perspective view of a shoe sole showing my new design;

FIG. 2 is a bottom perspective view thereof;

FIG. 3 is a left side elevational view thereof;

FIG. 4 is a bottom plan view thereof;

FIG. 5 is a right side elevational

FIG. 6 is a top plan view thereof;

FIG. 7 is a front elevation view thereof; and,

FIG. 8 is a rear elevation view thereof.

The broken lines showing a shoe upper in FIGS. 3, 5, 7, & 8 illustrate the portion of the design that forms no part of the claim.
